United States Patent Office.

JAMES FREDERIC TRAVIS, OF NEW YORK, N. Y.

Design No. 3,256, dated November 17, 1868.

DESIGN FOR THE BRANCH OF A GASOLIER.

The Schedule referred to in these Letters Patent and making part of the same.

To all whom it may concern:

Be it known that I, JAMES FREDERIC TRAVIS, of the city, county, and State of New York, have originated a new Design for the Branches of Gasoliers, of which the following is a full, clear, and exact description, reference being had to the accompanying photograph, forming a part of this specification.

The new and ornamental design for the branches of gasoliers and chandeliers, represented in the accompanying photograph, consists of a branch, A, which is made up of an upwardly-curved formation, a, of semi-circular form in its transverse section, and inwardly-scalloped border, as shown, and ending above in a scroll-like termination, e. Upon said termination e is supported a statuette, b, representing a sleeping fairy in a sitting posture, with forwardly-inclined head, arms relaxed, and feet crossed, and with upwardly-extended wings, c, of a formation as represented in the accompanying view. Downwardly and outwardly from the said scroll-like termination, e, is an inclined formation, d, terminating at the feet of the statuette b, by a step-like abutment, o, forming thereby a rectangular notch under the feet of the said statuette, as shown.

Immediately below this incline d, and step-like formation o, and fitting under the same by acute and rectangular points, g g', is an enlargement, h, of oblong formation in its transverse section, and provided near its edge with a recessed border, and is otherwise of a formation as represented in the accompanying view.

Projecting in a horizontal direction from said enlargement h and step-like formation o, is an upwardly-curved extension, k, of a semicircular formation in its transverse section, enlarging towards its outer extremity, and terminating, by means of its upwardly-curved extremity, in a horizontal platform, m, as represented in the photograph.

What I claim as my invention, and desire to secure by Letters Patent, is—

The design for the branch of a gasolier, substantially as herein shown and described.

JAMES F. TRAVIS.
